UNITED STATES PATENT OFFICE.

THEODORE C. VESEY, OF WEST POINT, MISSISSIPPI, ASSIGNOR OF ONE-SIXTH
TO SIDNEY B. WHITE, OF SAME PLACE.

FIRE-GRAVE.

SPECIFICATION forming part of Letters Patent No. 356,084, dated January 11, 1887.

Application filed February 8, 1886. Serial No. 191,178. (No model.)

To all whom it may concern:

Be it known that I, THEODORE C. VESEY, a citizen of the United States, and a resident of West Point, in the county of Clay and State 5 of Mississippi, have invented certain new and useful Improvements in Fire-Grates; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved grate. Fig. 2 is a vertical sectional view of the same. Fig. 3 is a perspective view from the rear of the fire-back; and Fig. 4 is a vertical sectional view showing the damper turned entirely up to cut off draft.

20 Similar letters of reference indicate corresponding parts in all the figures.

My invention has relation to fire grates; and it consists in the improved construction and combination of parts of the same, as hereinafter more fully described and claimed.

In the accompanying drawings, the letter A indicates the forward wall of the chimney, against which the fire-place is built. The jambs of the fire-place, which jambs are lettered B B in the drawings, have flanges C C projecting outward a short distance above the grate D, and these flanges are continued at the top of the fire-place in a flange, E, projecting from the top piece or lintel of the fire-place, 35 the said flanges forming a hood at the upper portion of the fire-place. The fire-back F extends obliquely out from a short distance above the bottom of the grate to near the top of the fire-place, and has flanges G G at its 40 side edges, and this back and the flanges are formed with ribs H crossing each other, which ribs serve to re-enforce the fire-back and its flanges, which are made of iron, and which would be liable to warp or bulge out if they 45 were not re-enforced by the said ribs.

The upper edge of the fire-back, which stops a short distance from the top of the fire-place, bears against the outer edge of a plate or shelf,

I, projecting from the wall of the chimney, and a damper, J, is located upon said shelf. 50 Trunnions K are formed upon the ends of said damper, in line with its rear edge, and turn in bearings in the jambs, one of said trunnions being provided with the usual form of damper-handle. The outer edge of the damper is bent 55 down to form a flange, L, which prevents any cinders or soot from accumulating upon the said shelf when the damper is raised, as such accumulations would prevent the damper from being lowered to a horizontal position when 60 desired. As this damper extends from jamb to jamb, and as its front edge is adapted to be moved from the upper edge of the fire-back to the lintel, the draft may be most perfectly 65 regulated.

The ribs upon the fire-back will prevent the heat of the fire from warping the fire-back and its flanges, and the oblique fire-back and the damper will prevent the heat from passing up in the chimney, the fire-back deflecting the 70 heat out into the room.

The fire-place may be used for burning either coal or wood, the grate being dispensed with when wood is burned.

Having thus described my invention, I claim 75 and desire to secure by Letters Patent of the United States—

In a fire-place, the combination of the jambs B, a top piece or lintel, the projecting flanges C and E, a fire-back projecting obliquely upward to near the top of the fire-place, a horizontal plate projecting from the front wall of the chimney to the upper edge of the fire-back, and a damper above the said plate and having its forward edge bent downward, and formed 80 with laterally-projecting trunnions at its rear corners, as and for the purpose shown and set forth.

In testimony that I claim the foregoing as my own I have hereunto affixed my signature 85 in presence of two witnesses.

THEODORE C. VESEY.
